UNITED STATES PATENT OFFICE.

FRANK E. PARTRIDGE, OF NEW ROCHELLE, NEW YORK, ASSIGNOR TO OX FIBRE BRUSH COMPANY, OF NEW YORK, N. Y., A CORPORATION OF WEST VIRGINIA.

DESIGN FOR A BRUSH-BACK.

52,807.

Specification for Design.

Patented Dec. 24, 1918.

Application filed December 6, 1917. Serial No. 205,899. Term of patent 14 years.

To all whom it may concern:

Be it known that I, FRANK E. PARTRIDGE, a citizen of the United States, residing at New Rochelle, in the county of Westchester and State of New York, have invented a new and original Design for Brush-Backs, of which the following is a specification, reference being had to the accompanying drawing, forming part thereof.

In the drawing—

Figure 1 is a plan of a brush back showing my new design;

Fig. 2 is a view of one side of the brush back;

Fig. 3 is a view of the opposite side thereof, and

Fig. 4 is a view of one end of the brush back.

In the figures brush material is represented in dotted lines for the purpose of illustrating its relation to the back.

I claim—

The ornamental design for a brush back, substantially as shown and described.

FRANK E. PARTRIDGE.
